CHARLES W. TERWILLIGER, OF BROOKLYN, NEW YORK.

SAFETY DEVICE FOR EXTRACTORS.

Application filed June 15, 1927. Serial No. 199,031.

This invention relates to safety devices for preventing the opening of the cover to a machine while the interior working parts are in operation and for preventing the starting of the machine while said cover is opened, the same being particularly designed for use in connection with centrifugal extractors used in laundries.

One of the principal objects of the present invention is to provide an improved attachment for extractors which eliminates the accidental opening of the cover while the machine is in operation or the accidental starting of the machine while the cover is opened. The invention more specifically contemplates an improved safety attachment for extractors which includes means for locking the cover in a closed condition, which means is operable by a governor on the drive shaft to dispose the same in a locked position when the drive shaft is active.

The invention furthermore comprehends means for preventing the manipulation of the lever to render the machine active when the cover of the machine is in an opened condition.

Other objects reside in the provision of an improved safety attachment for extractors, which is simple in its construction and mode of operation, which is inexpensive to manufacture and install, and which is thoroughly reliable and highly efficient in its purpose.

With the above recited and other objects in view, reference is had to the following description and accompanying drawings in which there are exhibited certain examples or embodiments of the invention while the appended claims define the actual scope of the invention.

In the drawings—

Figure 1 is a top plan view of an extractor equipped with a safety attachment constructed in accordance with the invention and illustrating respectively in full and dotted lines, the locked and unlocked condition of the cover;

Fig. 2 is a side elevation thereof;

Fig. 3 is an enlarged sectional view through the governor constituting a part of the safety attachment and which controls the locking device;

Fig. 4 is a transverse sectional view taken approximately on the line 4—4 of Fig. 3;

Fig. 5 is a plan view of a modified form of the invention installed on an extractor of a slightly different type than that illustrated in Fig. 1;

Fig. 6 is a side elevation thereof;

Fig. 7 is a fragmentary sectional view taken approximately on the line 7—7 of Fig. 5;

Fig. 8 is a fragmentary sectional view taken approximately on the line 8—8 of Fig. 5.

Referring to the drawings by characters of reference, A designates the extractor body which is provided with a cover B hingedly connected thereto by the hinge C and adapted to be swung from its closed position upwardly and rearwardly to an open position. A countershaft D is suitably supported in rear of the extractor and has secured thereto a main drive pulley E around which a belt F is trained leading to and operating the interior mechanism of the extractor (not shown) when the drive pulley E is rotated with the shaft D. The shaft D carries the usual live pulley G and idler pulley H, the former being secured to the shaft D and the latter being loosely mounted thereon. A belt I trained around a suitable driven element (not shown), is shiftable respectively from the pulley G to the pulley H and vice versa by a shifting means J manually operable by a manipulating lever K which is disposed in rear of the cover B and obstructed by said cover B when the same is in its open position. Ordinarily the operator is required under this practice to swing the cover B forwardly and downwardly to its closed position before access can be had to the manipulating lever K to shift the belt I on to the live pulley G when the machine is at a standstill.

In order, however, to lock the cover in its closed condition to prevent opening of the same while the machine is in operation, a swinging latch 10 is fulcrumed at 11 on a suitable bracket 12 and the nose 13 of said latch is normally disposed out of engagement with a keeper lug 14 by means of a coiled contractile spring 15 which is connected respectively to the arm 16 of the latch and to a bracket arm 17 of the bracket 12. The arm 16 is disposed in the path of movement of an axially movable push element 18 which is connected with a movable frame 19 carried by a

sleeve 20. The frame 19 supports a pair of substantially diametrically disposed governor elements 21 which are fulcrumed at 22 to the frame and are provided with weighted arms 23 and segment arms 24 having intermeshing teeth 25, a coiled contractile spring 26 serving to normally swing the weighted governor arms inwardly. The sleeve 20 is splined at 27 for axial sliding movement on a tubular boss 28 forming a part of a casing 29, which is secured to the shaft D by a set screw or equivalent means 30 for rotation with the shaft. The segment arms 24 are provided with cam terminals 31 which engage the end of the shaft D and the tubular boss 28. The casing 29 is provided with an aperture 32 in its outer end through which the element 18 is projectible.

In use and operation, when the cover B is closed and the operator starts the machine by turning the manipulating handle K to cause the shifting means to shift the belt I on to the live pulley G, the rotation of the shaft D and the governor means therewith, causes, by centrifugal force, the outward swinging movement of the weighted governor arms 23 to the position illustrated in dotted lines in Fig. 3. This movement of the governor arms causes the segments 24 to engage with the end of the shaft D and tubular boss 28 and move the sleeve 20 and frame 19 outwardly to project the element 18 through the aperture 32 and to engage the arm 16 of the latch 10, thereby swinging the nose 13 against the action of the spring 15 over the keeper lug 14. This effectually locks and maintains the cover B in a locked closed condition as long as the machine is in operation. When the machine is stopped by swinging the handle K in a direction to shift the belt I on to the idler pulley H, the stopping of the shaft D permits the weighted governor arms 23 to return the governor to a normal position where the element 18 is retracted allowing the spring 15 to function to swing the latch 10 to the dotted-line released position illustrated in Fig. 1. In view of the fact that the cover B in its opened condition obstructs ready access to the handle K, it is obvious that accidental starting of the machine without first closing the cover B, is obviated.

In the form of the invention illustrated in Figs. 5 to 8, inclusive, the operating lever L which controls the shifting fork M carried by the slide shaft N, is disposed in a position where it is not obstructed by the open cover B of the extractor A. Hence, in order to prevent starting of the machine with the cover opened, means actuated by the cover is provided for preventing the starting of the machine when the cover is open. As illustrated, this means consists of a sliding bolt 35 mounted in a bearing 36 and normally retracted by a spring 37 out of the path of movement of the slide shaft N which carries the shifting

fork. The cover B has secured to the hinge pin C for turning movement therewith a cam 38, the high point 39 of which engages with the inner end of the sliding bolt and projects the opposite end outwardly into the path of movement of the slide shaft N when the cover is in opened position as illustrated in Fig. 7.

When the cover is in closed condition as illustrated in Figs. 5 and 6, the low point or surface 40 of the cam is disposed in a position to permit the spring 37 to move the sliding bolt 35 inwardly to retract the outer end from a position in the path of movement of the slide shaft N so that the manipulating handle L may be employed to shift the slide shaft N and shifting fork M in a position to engage the belt I on the live pulley G for operating the machine. In this form of the invention, the safety device or attachment previously described in the first form of the invention is employed and operates in the same manner for locking and maintaining the cover in locked position until the machine stops.

What is claimed is:

1. In a power operated extractor or the like having a casing and a cover, means for locking the said cover in closed condition, comprising a pivoted lock arm adapted for movement respectively to locking and unlocked positions for obstructing and permitting opening movement of the cover, means for normally swinging the lock arm to an unlocked position, and centrifugally actuated means carried by a rotating part of the machine for engaging and swinging the lock arm to a locked position, said centrifugally actuated means comprising a casing operatively connected with a rotating part of the machine for rotation, said casing having an axially extending internal support, a member splined thereon for rotation therewith and for axial sliding movement, weighted arms pivoted thereto, said arms having cam terminals engageable with said support and adapted upon outward swinging movement of the arms by centrifugal force to slide the member axially, and an actuator element carried by said member and engageable with the lock arm for moving the same.

2. In a power operated extractor or the like having a casing and a cover, means for locking the said cover in closed condition, comprising a pivoted lock arm adapted for movement respectively to locking and unlocked positions for obstructing and permitting opening movement of the cover, means for normally swinging the lock arm to an unlocked position, and centrifugally actuated means carried by a rotating part of the machine for engaging and swinging the lock arm to a locked position, said centrifugally actuated means comprising a casing operatively connected with a rotating part of the machine for rotation, said casing having an

axially extending internal support, a member splined thereon for rotation therewith and for axial sliding movement, weighted arms pivoted thereto, said arms having cam terminals engageable with said support and adapted upon outward swinging movement of the arms by centrifugal force to slide the

member axially, and an actuator element carried by said member and engageable with the lock arm for moving the same, the said cam terminals having toothed interengaging segment portions.

CHARLES W. TERWILLIGER.
